(57) **CLAIM**

The ornamental design for a combined blow dryer and hair iron, as shown and described.

DESCRIPTION

FIG. 1 is a front right side perspective view of a combined blow dryer and hair iron showing our new design, the blow dryer in a closed condition;

FIG. 2 is a right side elevation view of FIG. 1;

FIG. 3 is a left side elevation view of FIG. 1;

FIG. 4 is a front elevation view of FIG. 1;

FIG. 5 is a rear elevation view of FIG. 1;

FIG. 6 is a top plan view of FIG. 1;

FIG. 7 is a bottom plan view of FIG. 1;

FIG. 8 is a front right side perspective view of the combined blow dryer and hair iron in an open condition; and,

FIG. 9 is a front left side perspective view of FIG. 8.

The broken lines in the drawings depict portions of the combined blow dryer and hair iron that form no part of the claimed design.

1 Claim, 7 Drawing Sheets
